(57) **CLAIM**

The ornamental design for a base station for a multimedia device remote control system, as shown and described.

DESCRIPTION

FIG. 1 is a front, top and right side perspective view of a base station for a multimedia device remote control system showing my new design;

FIG. 2 is a front elevational view thereof;

FIG. 3 is a top plan view thereof;

FIG. 4 is a rear elevational view thereof;

FIG. 5 is a bottom plan view thereof;

FIG. 6 is a left side elevational view thereof; and,

FIG. 7 is a right side elevational view thereof.

The broken lines, which define the boundary of the claimed design, form no part thereof.

The broken lines shown in the figures form no part of the claimed design.
